STOCK SHED DOOR

Filed May 8, 1923

Patented Mar. 24, 1925.

UNITED STATES PATENT OFFICE.

JOHN A. SPIČKA, OF WESTON, NEBRASKA.

STOCK-SHED DOOR.

Application filed May 8, 1923. Serial No. 637,513.

To all whom it may concern:

Be it known that I, JOHN A. SPIČKA, a citizen of the United States of America, residing at Weston, in the county of Saunders and State of Nebraska, have invented certain new and useful Improvements in Stock-Shed Doors, of which the following is a specification.

This invention relates to new and useful improvements in stock shed doors.

An important object of the invention is to provide a door for stock sheds or the like that may be actuated by the animals housed therein for the purpose of allowing the same to enter and leave at will.

A further object of the invention is to provide an improved hinge for swinging stock shed doors wherein the doors may be displaced vertically or laterally from the limited arc of movement of an ordinary swinging door to allow for the hurried entrance of more than one animal at a time during the driving of a drove of animals into a shed.

25 A further object of the invention is to provide a flexible hinge for swinging doors wherein a larger hinging zone is provided than heretofore used for such structures.

30 A further object of the invention is to provide an improved locking means for a door equipped with the type of hinge referred to above.

35 Other objects and advantages of the invention will be apparent during the course of the following description.

In the accompanying drawing forming a part of this specification and in which like numerals are employed to designate like parts throughout the same,

40 Figure 1 is a front elevational view of a door frame with the improved type of door and hinge embodying this invention associated therewith,

Figure 2 is a longitudinal sectional view

45 taken on line II—II of Fig. 1.

Figure 3 is a fragmentary sectional view of the improved locking means employed in connection with the swinging door and flexible hinge embodying this invention.

50 Figure 4 is a front elevational view of a modification of the flexible hinge and swinging door embodying this invention and minus the locking means shown in Figs. 1 to 3 inclusive, and

55 Figure 5 is a longitudinal sectional view taken on line V—V of the modification

shown in Fig. 4 and shows the swinging door in dotted lines displaced vertically from the ordinary arc of a swinging door.

In the drawing, wherein for the purpose of illustration is shown the preferred embodiment of this invention, the numeral 6 designates the vertical side frame members of a shed door opening having associated therewith the transverse top piece 7 as shown. Referring particularly to Figs. 1 to 3, inclusive, the top piece 7 is provided with a longitudinally extending groove 8 that is adapted for receiving the upper transverse edge of a relatively large piece of flexible material 9 secured therein. Secured to the lower transverse edge of the flexible material 9 is a swinging door 10 that is provided at its upper end with a cutout portion 11 adapted for receiving the flexible hinge 12 which is secured therein by means of a clamping plate 12 which is retained in position by any suitable fastening means, such as rivets. Slidably engaging the opposite faces of the transverse top piece 7 are resilient strap members 13 that are provided with longitudinally extending slots 14 adapted for being engaged by the clamping bolts 15 whereby the said strap members may be retained in any desired adjusted position. By examining Fig. 3, it will be seen that the strap members 13 may be moved downwardly to engage the top portion of the swinging door 10 for the purpose of preventing free movement of the latter, thereby retaining the said door in substantially a locked condition. The lower transverse edges of the door 10 are provided with metallic plate members 16 having scalloped depressions 17 formed in their outer faces for the purpose of reinforcing the lower edge of the door. Should the door 10 be employed for sheds housing hogs or the like, the scalloped depressions 17 will aid the animals in rooting the door open.

Referring particularly to Figs. 4 and 5, it will be seen that the transverse top strip 7 is adapted for having the relatively large flexible hinge member 9^a secured thereto by means of the clamping strip 7^a, while the lower edge of the flexible hinge member 9^a is secured to the swinging door 10^a by means of a clamping strip 12^a. In Fig. 5 the door 10^a is shown in dotted lines in vertical displaced position with respect to the usual arc covered by a swinging door.

It will be seen that with the exceedingly

large hinging zone provided by the flexible hinge member 9 embodying this invention, that the swinging door 10 may be displaced vertically, as shown in dotted lines in Fig. 5, and may also be displaced laterally when positioned outwardly or inwardly of the vertical side frame members 6. The door may be further twisted on substantially a longitudinal axis for the purpose of allowing an animal to pass through the opening by forcing against one longitudinal edge of the door. It is believed that the other features of construction possessed by this invention will be clearly understood from the above detail description.

It is to be understood that the forms of this invention herewith shown and described are to be taken as preferred examples of the same, and that various changes in the shape, size, and arrangement of parts may be resorted to without departing from the spirit of the invention or the scope of the subjoined claim.

Having thus described the invention, I claim:—

The combination with a door frame including a lintel; of a rectangular flexible strip extending substantially from side to side of said frame and having its upper edge portion secured to said lintel, said strip depending below said lintel, and a door secured to and depending from the lower edge portion of said strip, the top of said door being spaced below the lintel, and resilient fingers carried by said lintel and mounted for vertical sliding movement thereon, said fingers being arranged in pairs with the fingers of each pair opposite each other and having inwardly bent lower ends bearing on the flexible strip when raised and on the upper part of the door when depressed.

In testimony whereof I affix my signature.

JOHN A. SPIČKA.
